CLAIM

The ornamental design for a water bottle, as shown and described.

DESCRIPTION

FIG. 1 is a perspective view of a water bottle showing my new design;

FIG. 2 is a front view thereof;

FIG. 3 is a rear view thereof;

FIG. 4 is a left side view thereof;

FIG. 5 is a right side view thereof;

FIG. 6 is an enlarged top plan view thereof for ease of illustration;

FIG. 7 is an enlarged bottom plan view thereof for ease of illustration;

FIG. 8 is a cross-section view thereof taken along line 8-8 in FIG. 6; and,

FIG. 9 is a cross-section view thereof taken along line 9-9 in FIG. 6.

In the drawings, the broken lines depict unclaimed subject matter and form no part of the claimed design.
